UNITED STATES PATENT OFFICE.

JOHN J. MUELLER, OF OTTAWA, ILLINOIS, ASSIGNOR TO AMERICAN NICKELOID COMPANY, OF PERU, ILLINOIS, A CORPORATION OF ILLINOIS.

ELECTROPLATING APPARATUS AND PROCESS.

Application filed October 8, 1921. Serial No. 506,457.

To all whom it may concern:

Be it known that I, JOHN J. MUELLER, a citizen of the United States, residing at 818 La Salle Street, Ottawa, in the county of La Salle and State of Illinois, have invented a new and useful Improvement in Electroplating Apparatus and Processes, of which the following is a specification.

This invention relates to electroplating apparatus and process and is fully described in the following specification and shown in the accompanying drawings, in which:

Figure 1 is a vertical longitudinal section through the entering end of the apparatus;

Fig. 1^a is a continuation of Fig. 1 through the discharge end of the apparatus;

Fig. 2 is a transverse vertical section on the line 2—2 of Fig. 1^a; and

Fig. 3 is a partial section on the line 3—3 of Fig. 2.

This apparatus comprises a cleaning tank 10 and an electroplating tank 11 together with means which will be described for continuously cleaning and electroplating long strips of sheet metal. To this end, a reel 12 is mounted upon a shaft 13 which is suitably journaled on the frame 14 which also serves to support the tanks 10 and 11.

Rollers 15 and 16 are suitably journaled above and at the ends of the cleaning tank 10. Rollers 17 and 18 are journaled within the tank 10 and below the level of the cleaning liquid therein.

The sheet of metal 19 is unwound from the reel 12 and passes between the gripping rolls 15 and 15^a under the rolls 17 and 18 and between the gripping rolls 16 and 16^a.

The sheet 19 then passes between the gripping rolls 20 and 20^a and around under the rollers 21 and 22 which are journaled beneath the level of the electroplating fluid in tank 11. It then passes up between the gripping rolls 23 and 23^a and 24 and 24^a and thence through between the heated pairs of rolls 25, 26, 27 and 28 and on to the re-winding reel 29 which is secured to a shaft 30 which is continuously driven by any suitable means, as by a pulley 31 and a belt 32.

The cleaning compound used in the tank 10 may be of any suitable composition and where it is desired that the sheet shall be given an initial coat of metal suitable anodes 33 are connected to the positive side of a suitable source of electric current represented by the generator 34 while the metal

rollers 15 and 16 are connected to the negative side of the same source of current, as shown in Fig. 1.

As the plate passes from the rolls 16, 16^a to the rolls 20, 20^a, water is sprayed upon both sides of the sheet 19 by means of spray pipes 35 and 36 thereby washing the cleaning compound from the sheet before it passes on the electroplating tank 11.

This tank has a series of anode plates 37 lying beneath the metal strip 19 which are connected to the positive side of a suitable source of electric current represented by the generator 38, the negative side of the generator being connected to the metal rollers 20 and 23. It will thus be seen that the circuit will be completed by the metal strip 19 which makes contact with the metal rollers 20 and 23 and that with a suitable electrolyte in the tank 11 metal will be deposited upon the strip 19 particularly on the underside of this strip which is nearest to the anode plates 37. As the plate 19 emerges from the tank 11 and passes between the rolls 23 and 23^a a large part of the electrolyte will be squeezed from the sheet and run back into the tank. A small amount, however, will stick to the sheet and will be washed off by a spray of water from the pipes 39 and 40 which lie between the pairs of rolls 23, 23^a and 24, 24^a.

The sheet then passes between the pairs of rolls 25, 26 and 27, 28 which are internally heated in any suitable manner and which are held firmly in contact with the sheet 19. Buffing wheels 41 and 42 are mounted upon shafts 43 and 44 respectively and are driven by any suitable source (not shown) at a much higher rate of speed than the rolls 25, 26 and 27, 28 so as to keep them highly polished.

It will thus be seen that the metal strip 19 as it travels from the reel 12 through the apparatus from left to right is cleaned, washed, electroplated, washed and dried and is then wound upon the rewinding reel 29 in a series of operations which are continuous.

In the case of a very thin sheet of metal it sometimes becomes necessary to feed current thereto at a point between the rollers 20 and 23 in the electroplating tank. For this purpose I have provided a series of disk-like rollers 45 which are mounted upon a shaft 46 as shown in Fig. 2 and which are placed

- immediately over rollers 47 which, like the rollers 17, 18, 21, 22, are non-metallic and non-conductors of current. The disks 45 are made of metal and are covered with a coating 48 of asphaltum or the like, except upon their peripheries. Electrical contact is thus permitted between the disks 45 and the sheet 19 and deposit of metal is prevented upon the disks 45 except on their peripheries.
- 10 The shaft 46, as shown in Fig. 2, is connected to the source of current 38 by means of a wire 49.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as possible in view of the prior art.

What I claim as new and desire to secure by Letters Patent is:

- 25 1. A machine for continuously electro-plating metal strips comprising a tank, anode plates in said tank, a suitable source of electrocurrent the negative side of which is connected to the ends of said strip extending out of said tank and the positive to said anode plates and a rolling contact connecting the negative to said strip within the tank.

- 30 2. A machine for continuously electro-

plating metal strips comprising a tank, anode plates in said tank, a suitable source of electrocurrent the negative side of which is connected to the ends of said strip extending out of said tank and the positive to said 40 anode plates, a rolling contact connecting the negative to said strip within the tank and a roller supporting said strip in contact with said rolling contact.

3. A machine for continuously electro-plating metal strips comprising a tank, anode plates in said tank, a suitable source of electric current the negative side of which is connected to the ends of said strip extending out of said tank and the positive to 50 said anode plates and a rolling contact connecting the negative to said strip within the tank, said rolling contact being substantially covered with an insulating substance except on its periphery.

4. The process of continuously plating an imperforate strip of metal consisting of continuously passing said strip through an electrolyte, applying an electric current thereto at a plurality of points while in the electrolyte, washing and drying said strip after being plated and winding said strip on a reel.

5. The process of continuously plating an imperforate strip of metal consisting of continuously passing said strip horizontally 65 through an electrolyte, applying an electric current thereto while in the electrolyte, washing and drying said strip after being plated and winding said strip on a reel.

JOHN J. MUELLER.
